(57) **CLAIM**

The ornamental design for a round bale mover and feeder, as shown and described.

DESCRIPTION

FIG. 1 is a three quarter front top left side perspective view of a round bale mover and feeder showing an embodiment of my new design having six bale lifting components;

FIG. 2 is a left side elevational view thereof taken in the direction of arrow 2 in FIG. 8, the right side elevational view being a mirror image thereof;

FIG. 3 is a left side elevational view of another embodiment, taken in the direction of arrow 3 in FIG. 8, with the brackets to illustrate that the precise length and the exact number of bale lifting components are non-specified;

FIG. 4 is a top plan of FIG. 1 taken in the direction of arrow 4 in FIG. 8;

FIG. 5 is a bottom plan view thereof, taken in the direction of arrow 5 in FIG. 8;

FIG. 6 is a front elevational view thereof, taken in the direction of arrow 6 in FIG. 8;

FIG. 7 is a rear elevational view thereof, taken in the direction of arrow 7 in FIG. 8; and,

FIG. 8 is a view identical to FIG. 1 with descriptive legend directional arrows included which are necessary for better understanding of the drawing in accordance with 37 CRF 1884(o) and appropriate with good engineering practices, so as to best indicate in what directions previous views are taken so that nothing regarding the design sought to be patented is ambiguous or left to conjecture.

1.) The tractors shown in FIGS. 1 and 8 in broken lines are for environmental purposes only and form no part of the claimed design; and

2.) Any portion of any figure shown in broken lines accompanied by a bracket indicates a part of indeterminate length and non precise number of bale lifting components.
